PILL DISPENSING DEVICE

John B. Felber, Cleveland, Ohio

Application September 2, 1937, Serial No. 162,082

2 Claims. (Cl. 312—88)

My invention relates to improvements in dispensing devices for pills, tablets or the like and is more particularly concerned with dispensing devices used in steel mills and the like, for delivering pills one at a time where employees are exposed to severe heat conditions.

This device is particularly designed for use in steel mills, foundries and the like where the workers are subject to the intense heat of the molten metal, etc. When the worker takes a drink of water he places one of these pellets or pills in his mouth. These pills are of a salty substance and taken with the water they ward off any bad effects that would otherwise be likely to result from drinking cold water while heated up.

The principal object of this invention is to provide a device of simple construction which will readily dispense the tablets without jamming and crushing.

Another object is to provide a device to which a magazine may be readily attached and changed at will when it becomes empty.

These and other objects and advantages may be noted from the following specification and its accompanying illustrations in which:

Fig. 1 is a side elevation of the device with the magazine in position.

Fig. 2 is a front elevation partly in section, with the dispensing mechanism in closed position.

Fig. 3 is a side elevation of the dispensing mechanism.

Fig. 4 is a front fragmentary section with the dispensing mechanism in elevation in open position.

Fig. 5 is a top plan view of the dispensing mechanism.

Fig. 6 is a section on line 6—6 of Fig. 5.

Fig. 7 is a section similar to Fig. 6 but showing the open position.

Again referring to the illustrations, a shell 10 has a tapered lower portion 11 terminating in a flange 12, a stationary or fixed cylinder 13, terminating in a bottom flange 14 and having a series of lips 15 projecting outwardly from the top thereof, is mounted within the tapered lower portion 11 of the shell 10, the flange 12 of the said shell being peaned at 16 over the bottom flange 14 of the stationary cylinder 13.

A washer 17 is mounted within the shell 10 and rests upon the lips 15 of the cylinder 13.

The stationary cylinder 13 has a gear wheel or pinion 18 mounted on the outside surface thereof on a shaft 19, adjacent to and projecting

slightly over a slot 20 in the wall of the said cylinder 13.

A movable inner cylinder 21 is slidably mounted within the stationary cylinder 13, a pair of slots 22 and 23 in opposed sides of said movable cylinder allows the cylinder to pass the gear shaft 19 as it moves up and down within the stationary cylinder 13.

A gear rack 24, secured to the outer surface of the movable inner cylinder 21, meshes with the gear 18 and moves up and down within the slot 20 in the stationary cylinder 13, a spring 25 secured by one end to the gear rack 24 and by its opposite end to the stationary cylinder 13, limits the upward movements of the movable inner cylinder 21 and draws said cylinder back to its original position when released.

A round tablet receptacle 26 having a circular recess or depression 27 in its top surface, is mounted within the movable inner cylinder 21, and secured to the shaft 19.

The device may be secured to a wall 28 by a strap 29 therearound and a magazine 30 mounted in the top thereof.

In operation, the movable inner cylinder 21 is pressed upward, the gear rack 24 being carried upward on the said cylinder within the slot 20 expanding the spring 25, the gear 18 meshing with the gear rack 24 is rotated and in turn rotates the tablet receptacle 26 on the shaft 19 until the recess or depression 27 in said receptacle is in the reversed position as shown in Fig. 7, the tablet 31 dropping into the hand. As the pressure on the movable inner cylinder is removed, the spring 25 compresses and draws the said movable cylinder back to its original position as indicated by Fig. 6, the tablet receptacle 26 again pivoting its position until the recess 27 is at the top and again receives a tablet.

I claim:

1. A dispensing device comprising a receptacle having a discharging mouth, a shell attached thereto, a stationary cylinder within and secured to the shell and extending between the discharging mouth and the exterior of the shell, a shaft extending across the cylinder and having a pill dispensing member mounted thereon and located within the stationary cylinder, a gear wheel attached to the shaft adjacent the outer surface of the cylinder, a telescopingly mounted reciprocating cylinder within the stationary cylinder, and having an end extending beyond the exterior end of the stationary cylinder, and a gear rack attached thereto, said gear wheel and gear rack

cooperating upon reciprocation of the cylinder to operate the pill dispenser, said movable cylinder having opposed slots for the shaft, and said stationary cylinder having a slot for the gear rack, and a spring connected between the gear rack and the stationary cylinder.

2. A dispensing device as in claim 1, the stationary cylinder having lips formed in the upper edge thereof, and a washer supported on the lips, the mouth of the receptacle being supported on the washer.

JOHN B. FELBER.
